UNITED STATES PATENT OFFICE.

HERMANN SIEGEL, OF NEW YORK, N. Y.

DESIGN FOR THE ORNAMENTATION OF GLASSWARE.

SPECIFICATION forming part of Design No. 21,383, dated February 2, 1892.

Application filed January 4, 1892. Serial No. 417,011. Term of patent 7 years.

To all whom it may concern:

Be it known that I, HERMANN SIEGEL, of New York, in the county of New York and State of New York, have invented a new and original Design for the Ornamentation of Glassware; and I do hereby declare the following to be a full, clear, and exact description of said invention, reference being had to the accompanying drawing, and to the letters of reference marked thereon, which forms a part of this specification.

The accompanying drawing, forming part of this specification, represents the ornamentation as applied to a shallow dish, and said drawing will be sufficient to enable others to apply the design to various articles of glassware.

The leading features of my design consist of a large central star, the longer points of which are inclosed by grooves convexed toward each other and meeting at points outside of said star-points and oppositely curved grooves crossing each other beyond said points, the spaces bounded by latter grooves having alternately stars and fields of fine crossed lines.

In the center of the design is a star A of a well-known pattern, the longer points a of which extend, each of them, into the space be-

tween two curved grooves or lines b b, which meet at a point b' in a radial line beyond the point a. Just outside of each point b' two oppositely curved deep grooves c c cross each other and meet the ends of the other grooves c c at points c' c' in a radial line beyond the center of the space between two points a. In the spaces bounded by the grooves c c c c there are formed, alternately, stars D, of a pattern similar to but smaller than star A and the finely-grooved fields E. In the spaces formed between each pair of crossed grooves c c and outside the points of crossing are the conventional fan-figures F, and in the long narrow spaces between grooves b b and the grooves c c are formed short parallel grooves g.

Having thus described and illustrated my invention, what I claim and desire to secure by Design Letters Patent, is—

The design for the ornamentation of glassware, substantially as herein shown and described.

In testimony whereof I affix my signature in presence of two subscribing witnesses.

HERMANN SIEGEL.
